UNITED STATES PATENT OFFICE.

MARTIN HARMON, OF ST. LOUIS, MISSOURI.

BUGGING-MACHINE.

1,242,546.

Specification of Letters Patent.

Patented Oct. 9, 1917.

Application filed June 20, 1917. Serial No. 175,851.

To all whom it may concern:

Be it known that I, MARTIN HARMON, a citizen of the United States, residing at St. Louis, State of Missouri, have invented certain new and useful Improvements in Bugging-Machines, of which the following is a full, clear, and exact description, reference being had to the accompanying drawings, forming a part hereof:

10 My invention has relation to improvements in bugging machines and consists in the novel features of construction more fully set forth in the specification and pointed out in the claims.

15 The present is an improvement on the construction of bugging machines forming the subjects-matter of my U. S. Patents numbered 755,769 dated March 29, 1904, and 890,051 dated June 9, 1908; and while con-

20 templating the several objects and possessing the several advantages of the patented structures, the improvement herein has for its object to provide an adjustable bug catching frame that may be raised or lowered to meet varying conditions. A further object is to provide an adjustable curtain wall or diaphragm above said frame against which the bugs may impinge when beaten from the plants. A further object is to provide a bent 25 guard over the end of the frame to prevent the bugs from crawling out and escaping. Further advantages will be better apparent from the following detailed description of the invention in connection with the accompanying drawings in which—

Figure 1 represents a plan of the invention, parts being broken away; Fig. 2 is a side elevation with the rear wheel and shafts removed; Fig. 3 is a front elevation with parts broken away; Fig. 4 is a vertical cross-section on the line 4—4 of Fig. 1; and Fig. 5 is an outline or diagrammatic view of the roller frame and roller-drive mechanism in various positions.

40 Referring to the drawings, F, represents a frame made up of bent longitudinal angle bars 1, 1, side terminal angle bars 2, 2, and braces 3, 3, secured to the transverse bolster 4 and to an angle bar 5 at the fore part of the frame. The angle bars 1, 1, are also secured to a bolster 6 at the rear part of the frame. Secured to the angle braces 3, 3, are the usual shafts 7, 7, and hinged to the inner terminals of the angle bars 2, 2, is an

angle bar 8, said bar being provided with 55 upturned lugs or brackets 8' which are pivotally and directly coupled to said angle bars 2, 2. The oscillating bar 8 is adapted to be operated by a shift lever 9 in a manner to be hereinafter more particularly referred 60 to. Secured to the rear bolster 6, and projecting rearwardly therefrom, are a pair of brackets 10, 10, between which is rotatably mounted a bearing wheel 11.

Mounted in suitable bearings 12 depending from the frame F, are a pair of axle-shafts A, A, the outer ends of which carry the wheels W, a drive-gear 13 being mounted on each shaft at about the middle point thereof. Meshing with each gear 13 is a 70 pinion 14 mounted on the front end of a longitudinal shaft 15 on which is also mounted a five-bladed beater 16.

A platform P is mounted on the frame F near the middle of the front part thereof and on the inside edge of said platform is secured a toothed quadrant 17, an oscillating lever 18, and pawl 19 engaging the teeth of the quadrant, all of which is well understood in the art. To the lower end of the lever 80 18 are secured chains 20, 20', the same passing over a pulley 21, from which point the chain 20 passes through an opening o in the platform P and connects with an adjacent hanger 22 to which one end of the roller frame F' is secured. In the frame F' are mounted two pairs of crushing rollers r, r', r, r', spaced a suitable distance apart. Between each pair of rollers, and engaging the inner rollers r of the respective pairs is an 90 arched apron a; and engaging the outer rollers r', and disposed on the outside of the respective pairs of rollers and aprons b, b, the same dipping toward the rollers. The chain 20' passes from the pulley 21 over a pulley 95 23, thence to the opposite hanger 22, to which the corresponding end of the frame F' is secured, said chain 20' passing through openings o', o', in the brackets 10, 10. The rollers r, r', of each pair are geared together by gears g, g. The rollers r, r, of said pairs are provided with spindles 24, 24, on the ends of which are mounted sprocket wheels 25, 25; said sprocket wheels being driven by chains 26, 26, passing over them and over the driving sprocket wheels 27, 27, mounted on the shafts 15, 15, respectively. The shafts 15, 15, are slidable in

their bearings and may be shifted horizontally back and forth by the oscillating angle 8, the vertical leg of which is confined between the collars *c*, *c*, on each shaft 15. By 5 this means the pinions 14, 14, may be disengaged from the gears 13, 13, when the machine is being moved from place to place but is not operating.

Secured to the forward end of the frame 10 *F'* are guide bars 28, 28, adapted to pass freely through U-shaped guides 29, 29; and pivotally connected to each bar 28 is one end of a toggle lever 30. Pivotally secured to the bolster 4 on the outside of each bar 28 15 is a lever 31, said lever being coupled by a pin 32 to a lever 30 and forming a toggle joint therewith. A roller 33 is mounted on the pin 32, and a roller 34 is mounted on a pin 35 projecting from the lever 30 at about 20 the middle. The upper run of the chain 26 passes over the roller 33 and the lower run of said chain passes over the roller 34, said rollers taking up the slack of the chain when the frame *F'* is raised or lowered (Fig. 5) 25 as presently to be described. Mounted between a pair of brackets *d*, *d*, secured to the frame *F* along a central line between the angles 1, 1, is a roller curtain *C* disposed over the ridge of the arched apron *a* and 30 adapted to be raised or lowered depending upon the position of the frame *F'*.

In the operation, the machine is drawn between the rows of potato plants so that two rows are spanned by the wheels *W*, the 35 rear wheel 11 traveling in the furrow between the two rows thus spanned, while the beaters 16 are in contact with the plants. The shift lever 9 is then placed in the position shown, (Fig. 2) the pinions 14 engaging 40 the gears 13 whereby upon advancing the machine, the shafts 15 and beaters 16 rotate in a direction (see arrows in Fig. 3) to cause the bottom blades of the beaters to engage or impinge against the plants and 45 beat the bugs from them. The bugs then fall into the frame *F'* and are guided by the aprons *a*, *b*, to the rollers *r*, *r'*, between which they are crushed since the upper peripheries of the latter are caused to rotate 50 toward each other by the gears *g*, *g*, chain 26 and sprockets 25, 27. The aprons *a*, *b*, also act as scrapers to remove the crushed bugs from the rollers.

The roller curtain *C* acts as a partition 55 wall through the center of the machine and prevents the beaters from knocking the bugs over the frame *F'*, as they will impinge on the curtain and drop down into said frame. A bent guard *G* mounted across the rear 60 end of the roller frame *F'* prevents the bugs from crawling out of the frame as they will crawl up the guard and finally get to the depending edge thereof from which point

they will fall back into the frame and again land on the aprons *a*, *b*.

65

In operating the machine or in moving it from place to place it may be desirable to raise or lower the roller frame *F'* to allow for the contour of the ground. Since the said frame is suspended by the chains 20, 20', passing over the pulleys 21, 23, and from the pulley 21 to the lower end of the lever 18, it is obvious that by oscillating the lever 18 either forward or backward, the chains may be either released or pulled up 70 and the frame *F'* lowered or raised as desired. However, some provision must be made for taking up or letting out the drive chains 26 between the sprockets 25 and 27. This is done by means of the rollers 33, 34, 80 mounted on the levers 30, 31, arranged as toggles as explained above and shown in Figs. 3 and 5 (full and dotted positions).

It is within the purview of the skilled mechanic to vary the construction from that 85 here shown without departing from the spirit of the invention, the present form having been adopted since it is simple and has proven satisfactory in practice. Parts shown but not described are well understood 90 and need no description in this connection.

Having described my invention what I claim is:

1. In a potato bugging machine, a main frame, a pair of independent axles secured 95 thereto, drive gears on said axles, longitudinally extending shafts rotatable in the frame, beaters on the shafts, pinions on said shafts meshing with the drive gears, a vertically adjustable roller-frame suspended 100 from the main frame, a pair of crushing rollers in the roller-frame, one roller of each pair being provided with a sprocket wheel, said sprocket being engaged by a chain which also engages a drive sprocket on the 105 longitudinal shaft aforesaid, and a toggle provided with a pair of rollers each of which is traversed by one lap of the chain aforesaid, said toggle being adapted to take up the slack of the chain upon adjusting the 110 roller-frame.

2. In a machine of the character described, a movable frame, toggle-levers having one member hinged to a fixed support, the opposite member being pivotally secured to the 115 frame, crushing rollers in the frame, drive-chains for actuating said rollers, and means interposed between the toggle-levers and the drive-chain for causing the chain to conform 120 to the movements of the frame.

In testimony whereof I affix my signature, in presence of two witnesses.

MARTIN HARMON.
